MUFFLER WITH FLASHING AND SPARK ELIMINATING MEANS

Burr C. Folts, Herkimer, N. Y.

Application August 6, 1952, Serial No. 302,946

2 Claims. (Cl. 181—57)

This invention relates to a muffler for internal combustion engines and has particular reference to a muffler which is constructed and arranged to attenuate the sound waves and to eliminate flashing of the exhaust gases and the discharge of sparks.

Since exhaust gases from internal combustion engines are discharged at high pressure and high velocity, high pressure pulses are produced which result in peaks in the sound waves unless the sound waves are attenuated. Furthermore, the exhaust gases include unconsumed gases of combustion which frequently ignite producing a flashing and an explosive sound and the discharge of sparks.

An object of the present invention is to provide a muffler which attenuates the peaks of the sound waves so as to dampen the explosive sounds and which prevents the flashing through the muffler of unconsumed gases as well as eliminating the discharge of sparks.

Another object of the invention is to provide a muffler having spaced expansion chambers formed with perforated walls for directing the flow of the exhaust gases in the form of streams into attenuating chambers and having a chamber located adjacent the outlet thereof which is separated from a surrounding attenuating chamber by an inner wall and an overlying screen providing a flashing and spark eliminating means.

Another object of the invention is to provide a muffler of said character having an outlet chamber adjacent the outlet opening which is closed at the inner end and provided with a foraminous peripheral wall and an overlying screen which separates the outlet chamber from a surrounding chamber.

With the foregoing and other objects in view, reference is now made to the following specification and accompanying drawings in which the prevailing embodiment of the invention is illustrated.

In the drawings:

Fig. 1 is a longitudinal sectional view of a muffler constructed in accordance with the invention.

Fig. 2 is a cross-sectional view taken approximately on line 2—2 of Fig. 1.

Fig. 3 is a cross-sectional view taken approximately on line 3—3 of Fig. 2.

Referring to the drawings by characters of reference, the muffler includes a tubular shell 11 which is closed at its ends by heads 12 and 13. The head 12 has a tubular extension 14 forming an inlet 15 and providing means for connecting the muffler with the exhaust manifold of an internal combustion engine, and the head 13 has a tubular extension 16 forming a discharge outlet 17.

The muffler is provided with means for attenuating the sound waves produced by the exhaust gases admitted through the inlet 15 and with means for preventing the flashing of unconsumed gases through the outlet 17 as well as arresting sparks within the muffler and preventing the discharge thereof. For this purpose, the muffler is provided with partitioning walls 18, 19, and 20 which are secured to the inner face of the shell in longitudinally spaced relation. The walls 18 and 19 are centrally ap-

2

ertured and secured thereto about the apertures therein is an apertured shell 21 disposed in alignment with the inlet 15. The wall 18 being spaced from the head 12 provides an expansion chamber 22 adjacent the inlet 15 and the walls 19 and 20 provide an expansion chamber 23 at the outlet of the apertured shell 21. The shell 21 is provided with a plurality of longitudinally and radially arranged rows of inwardly offset louvers 25 having forwardly disposed openings 26 for directing a portion of the exhaust gases flowing through the shell 21 into the surrounding chamber 27 in the form of streams or whirls to thereby produce a turbulence of the gases in the surrounding chamber 27 and attenuate the peaks of the sound waves.

The wall 19 is formed with concentric rows of outwardly directed louvers 29 providing inwardly directed openings 30 through which the exhaust gases are discharged from the chamber 27 into the expansion chamber 23. The exhaust gases admitted through the inlet 15 expand in the chambers 22 and 23 with a consequent reduction in the velocity of the flow so as to diminish the peaks of the sound waves while the turbulence in the gases produced in the chamber 27 and in the chamber 23 by the arrangement of the louvers 25 and 29 effects a further attenuation of the peaks of the sound waves.

Adjacent the outlet 17, the muffler is provided with an outlet chamber 32 disposed in alignment with the outlet 17 and which is closed at its inner end by the partition wall 20. Secured in fixed position between the partition wall 20 and the head 13 is a foraminous shell 33 in which the openings 34 are spaced apart substantially a distance corresponding to the cross-sectional dimension of the openings. The said shell forms the peripheral wall of the chamber 32 and separates the same from a surrounding chamber 35 located between the partition wall 20 and the head 13. Overlying the foraminous shell 33 is a fine mesh screen 36 which is in contact with the outer periphery thereof and overlies the openings 34 as well as the intervening portions thereof.

The partition wall 20 is formed with concentric rows of openings 37 for the flow of exhaust gases from the chamber 23 into the chamber 35 surrounding the outlet chamber 32. The partition wall 20 thus functions to eliminate practically all possibility of ignition of unconsumed gases in the chamber 35 and the foraminous shell 33 and overlying screen 36 function to eliminate flashing of the gases in the outlet chamber 32 and the discharge of sparks therethrough. While finely divided glowing carbon particles frequently pass with the exhaust gases into the muffler, such particles will be arrested in the chamber 35 by means of the peripheral wall 33 and screen 36. The screen 36 is of sufficiently fine mesh to prevent the discharge of ordinary size carbon particles from falling therethrough and retains the same in the chamber 35. A 40 mesh screen has been found to be satisfactory but the same is not limited to such mesh screen. The screen is of corrosive-proof material which will withstand the corrosive action of fumes and gases in the exhaust gases and given off by the carbon particles.

In order to clean out the chamber 35 and to remove the deposit of carbon particles, the head 13 is made up of a removable section 38 and a fixed section 39 having a peripheral flange 40 secured to the inner face of the tubular shell 11. The removable section 38 has the tubular extension 16 formed as an integral part thereof and this section is removably secured to the fixed section 39 by means of a plurality of radially arranged bolts 41 extending through aligned openings in the said sections. The section 38 may be readily removed by removing the bolts 41 so as to gain access to the chamber 32 within the peripheral wall 33 as well as the chamber 35.

The partition wall 20 is formed with an offset central portion providing an annular shoulder 43 and the remova-

ble section 38 of the end wall 13 is formed with an offset central portion forming an annular shoulder 44. The shoulders 43 and 44 extend toward each other and the foraminous shell 33 and screen 36 fittingly engage about said shoulders at their ends for securing the same in fixed position between the partition wall 20 and end wall 13.

What is claimed is:

1. In a muffler, a metal casing having inner and outer end walls provided with inlet and outlet openings respectively, a partition wall disposed intermediate said end walls, a foraminous tubular wall secured in fixed position between said partition wall and said outer end wall with the outer end of said tubular wall surrounding the outlet opening to thereby provide an outlet chamber in communication with the outlet opening and a chamber surrounding said tubular wall and located between the same and said casing, said partition wall closing the inner end of said outlet chamber and having apertures opening into said surrounding chamber for the flow of exhaust gases into said surrounding chamber and through said tubular wall into the outlet chamber, and a wire screen surrounding and closely fitting said tubular wall for arresting sparks passing with the exhaust gases and for preventing flashing of unconsumed gases in the outlet chamber.

2. In a muffler, a metal casing having inner and outer end walls provided with inlet and outlet openings respectively, a partition wall secured to said casing intermediate

5 said end walls, a foraminous tubular wall secured in fixed position between said partition wall and said outer end wall with the outer end of said tubular wall surrounding said outlet opening to thereby provide an outlet chamber in communication with the outlet opening and a chamber surrounding said tubular wall and located between the same and said casing, said partition wall closing the inner end of said outlet chamber, a wire screen surrounding and closely fitting said tubular wall for arresting sparks passing with the exhaust gases, and said outer end wall including a section fixed to said casing and a section removably secured to said fixed section for cleaning out particles deposited in said surrounding chamber when the removable section is removed.
